FUEL SUPPLY SYSTEM WITH EMERGENCY SWITCHING MEANS

Frederick Henry Carey, Cheltenham, England, assignor to Dowty Equipment Limited, Cheltenham, England

Application January 14, 1948, Serial No. 2,342
In Great Britain December 24, 1947

9 Claims. (Cl. 158—36.3)

1

This invention relates to liquid fuel supply systems for aircraft continuous combustion gas turbines having burners of the spill type, and comprising essentially two pumps of which one, a circulating pump, operates normally as a fixed delivery unit to circulate fuel in a circuit including the burners and the other, a supply pump, operates normally as a variable delivery unit to inject fuel into the circulating flow as necessary to maintain a required engine speed or to effect any change thereof. A spill type burner is herein defined as a burner in which, except during certain operating conditions, only a proportion of the fuel supplied to the burner passes out through the burner discharge orifice and the remainder passes back along a return line. Such a system is hereinafter referred to as "a system as herein specified."

The present invention seeks to provide an improved arrangement in such a system, whereby it is possible to maintain an adequate emergency fuel supply from one pump, thus avoiding complete failure of the system in the event of failure of either pump, and to this end and in accordance with the invention, the normally fixed delivery circulating pump is capable of emergency operation as a variable delivery unit, and means are provided whereby failure of either pump results in emergency operation of the still operative pump to deliver fuel from the tank to the burners. During emergency operation the return line from the burners would ordinarily be closed, and the burners would function as simple direct-injection burners so long as the emergency continues.

In defining the system with which the invention is concerned, the circulating pump is stated to operate normally as a fixed delivery unit. It is conceivable to vary the operation of the circulating pump without interfering with the basic principle of the system, for instance by simultaneously inversely varying the action of the supply pump, and it is to be understood that the invention covers such operation.

In order that the invention may be more clearly understood and readily carried into effect, a system in accordance therewith will now be described by way of example with reference to the accompanying diagrammatic drawings of which:

Figure 1 shows the system with the components in a position for normal operation;

Figure 2 shows an emergency operation with the supply pump having failed;

Figure 3 shows an emergency operation with the circulating pump having failed; and

2

Figure 4 shows a detail modification of the system of Figure 1.

The basic principles of the system, and the form and manner of operation of the individual burner nozzles, are disclosed in some detail in the copending application, Serial No. 2,343, filed coincidentally herewith, now Patent No. 2,608,247 issued August 26, 1952.

Referring to Figure 1 herein, the basic system operates during normal running in the following manner. A circulating pump 1 driven by the engine operates as a fixed delivery pump and circulates fuel around a circuit defined by a first conduit means including the pump discharge line 38, a burner supply line 2, a burner ring 3, burners 4 (only one of which is shown), a collector ring 5, return line 6, and pump suction line 43. A supply pump 7 which is also engine driven operates as a variable delivery pump and withdraws fuel by way of line 87 from a supply tank 8 and passes it through a supply line 9 including a metering valve or throttle 10, to inject fuel into the circulating flow at a convenient junction point 26 in the return line 15 6 running from the burner ring 5 to the inlet of the circulating pump 1. The lines 87 and 9 constitute a second conduit means.

The circulating and supply pumps are of similar design and each comprises a radial cylinder assembly 11 with a number of pistons 12 constrained to reciprocate within a track ring 13 the eccentricity of which with respect to the radial cylinder assembly determines the operative strokes of the pistons. The track ring 13 has a projecting finger 14 controlled by a pressure-loaded plunger, designated 15 in the case of pump 1 and 15' in the case of pump 1, which is urged by a spring 16 or 16' towards a position of maximum eccentricity of the track ring. The plunger 15 or 15' has a pressure face 17 or 17' respectively which responds to a pressure controlling the position of the plunger. The pumps 1 and 7 are also each of the type which develop centrifugal pressure within the space between the track ring 13 and its casing 18.

The system also includes a circuit control valve having a cylinder 19 and a multi-piston valve member 20, an isolating valve 21, an emergency control valve 22, and non-return valves 23 and 24 in the burner supply line 2 and return line 6 respectively. There is also shown, in its open position, a low pressure cock 25.

When the system is functioning normally, as shown in Figure 1, the pressure face 17' of the plunger 15' of the circulating pump 1 is, through the branch line 42 and the passage 26 of the

emergency control valve 22, exposed merely to the pressure of fuel within the tank 8 with the result that the spring 16' is able to maintain the track ring 13 of this pump 1 permanently in a position of maximum eccentricity so that the circulating pump functions normally as a fixed delivery pump. The pressure face 17 of the plunger 15 of the supply pump 7 is exposed by way of the line 41 to the supply pump delivery pressure and the supply pump 7 thus accommodates itself to variations in the setting of the metering valve 19 to maintain a constant pressure of fuel in its supply line 9. Thus, when the metering valve 10 is moved to restrict the flow through the valve, the pressure in the line 9 between the valve and the pump 7, and hence in the branch line 41, tends to rise with the result that the plunger 15 of the supply pump moves against its spring 16 to reduce the stroke of the pump until the original pressure in the line 9 is reached. Also, in the normal running condition, a spring 28 maintains the movable element 27 of the emergency control valve 22 in the position shown in Figure 1, and likewise a spring 30 maintains the movable element 29 of the isolating valve 21 in the position shown. Flow in the supply line 2 to the burners maintains the non-return valve 23 open to permit such flow, and the non-return valve 24 is similarly opened by the return flow in the line 6.

The pumps are generally designed so that there can be no major failure unless it be interruption of the actual drive of the pump, for example through a coupling which is sheared by overload. Let it be assumed that for some reason the supply pump 7 fails, and in order to represent that condition it has been omitted from Figure 2. In that condition the supply pump must be isolated from the system, which in fact occurs automatically. It will be seen that the multi-pistoned member 20 of the circuit control valve is subjected at its opposite ends (by way of pressure lines 44 and 45) to the centrifugal pressures developed within the respective pump casings 1 and 7, the lower end of the member 20 being exposed via line 44 to the centrifugal pressure in the circulating pump 1 and the upper end via line 45 to the centrifugal pressure in the supply pump 7. The area exposed to supply pump pressure is somewhat greater than that exposed to circulating pump pressure, and this, plus gravity, biases the piston member 20 into the normal position of Figure 1. Failure of the pump 7 means a cessation of the centrifugal pressure in its casing with the result that the piston member 20 of the circuit control valve moves up from the position shown in Figure 1, under the influence of circulating pump centrifugal pressure via line 44, to an emergency position shown in Figure 2. A spring (not shown) may be used to assist in its raising. Directly this happens, fuel delivered by outlet line 31 from the circulating pump 1 can no longer pass by way of burner supply line 2, but does pass through the circuit control valve 19 and through the line 32 and branch line 33, to shift the plunger 15' of the circulating pump 1 in a manner to alter the pump's normal delivery rate. The pump 1 will then function as a variable delivery unit in exactly the same way as did the supply pump 7 prior to its failure. Pressure in the line 32 also shifts the movable element 27 of the emergency control valve 22 to the position shown in Figure 2 (the passage 26 containing a sufficient restric-

tion that this element will move to the right in opposition to spring 28) at which it breaks communication between line 42 and the pressure face 17' of plunger 15', but permits fuel to reach the pump 1 by way of line 42, the circuit control valve 19, and line 43, for delivery by way of line 31, circuit control valve 19, line 32, and lines 41 and 9 to and through the metering valve 10 to junction point 96, and along the return line 6 as far as the non-return valve 24, which now closes. Flow also occurs along a branch line 34 leading to the isolating valve. Flow in the line 34 raises the member 29 of the isolating valve against the spring 30 to permit the fuel to flow through a by-pass 35 and through passages 36 within the member 29. The fuel issuing through the isolating valve closes the non-return valve 23 (the line 2 being also closed off at the circuit control valve 19) and flows along the remainder of burner supply line 2 to feed the burners 4. The system now functions on the circulating pump only, the delivery whereof is variable under the influence of delivery pressure applied at 17' by way of line 33, as already described, and the burners function as simple direct-injection burners (the burner return line 6 being closed by the valve 24). The conduit sections 42 from the reservoir to the intake side of the circulating pump 1 (by way of the circuit control valve 19), 32 from the output side of the circulating pump (by way of the circuit control valve) to and past the emergency control valve 22 and thence by conduit section 41 to the output side of the supply pump 7, for connection to the second conduit means in advance of the throttle means 10, and the branch conduit 34 off the second conduit means to the burner supply line 2 ahead of non-return valve 23, may be considered a third or emergency conduit means. The isolating valve 29 is included therein, and that portion of the second conduit means which includes the throttle means 10 may be considered as included also in the third conduit means. The third conduit means also branches, in the vicinity of the emergency control valve, to place the plunger 15' and its face 17' of the delivery-varying means of the circulating pump 1 under the influence of delivery pressure for automatic control when, under emergency conditions, only the circulating pump is operating.

Had it been the circulating pump which failed, which condition is represented by its omission in Figure 3, the delivery pressure from the circulating pump would fall and the element 29 of the isolating valve which is exposed at its upper end to such pressure would be lifted by the action of the delivery pressure from the supply pump in the branch line 34, acting always on its lower end, and the supply pump would then feed the burners through the isolating valve 21, at the same time closing the non-return valve 23 by way of pressure acting through lines 9 and 6. The absence of flow in the return line 6 due to the failure of the circulating pump would permit the supply pump to deliver thus along the line 6 to close the non-return valve 24. The system now functions with the supply pump alone, still acting as a variable-delivery pump, and with the burners operating as simple direct-injection burners.

In the modification shown in Figure 4, in which the same reference numerals are used to denote similar parts, the circulating and supply pumps 37 and 38 respectively are each of the fixed dis-

placement type. In normal operation, the circulating pump 37 operates as a fixed delivery pump and the supply pump 38 operates as a variable delivery unit comprising a by-pass circuit 39 and a relief valve 40. The supply pump 38 maintains a constant pressure in its delivery line by virtue of the relief valve 40 serving to by-pass more or less fuel in accordance with changes in the setting of the metering valve. In this arrangement, the need for the emergency control valve 22 of Figure 1 does not arise because the relief valve 40 can be used with the circulating pump 37 in the event of failure of the supply pump 38. Should the supply pump 38 fail, the circuit control valve 20 moves up to permit fuel delivered by the circulating pump 37 to flow along the line 41 leading to the metering valve 19 and to the relief valve 40. The down-stream side of the relief valve 40 then communicates with the inlet of the circulating pump 37 through the branch line 42, and through the circuit control valve 20 and line 43. Should the circulating pump fail, the emergency operation comes into being in the same way as in the arrangement described in connection with Figure 3.

I claim:

1. A fuel supply system, for the supply of liquid fuel in variable quantities under normal or under abnormal or emergency conditions to a spill type burner, particularly in an aircraft engine, said system comprising, in combination with a fuel reservoir, a normally operative circulating pump, a supply pump also and simultaneously normally operative, first conduit means constituting a closed circulation path arranged to lead from the output side of the circulating pump to the burner, and from the burner to the input side of the circulating pump, second conduit means leading from the reservoir to the return portion of the first conduit means through the supply pump, means operatively associated with the supply pump to vary its delivery automatically in accordance with the burner's requirements, throttle means in the second conduit means intermediate the supply pump and the connection to the first conduit means, to regulate the supply of fuel to the burner from the supply pump, a circuit control valve in the first conduit means subject to pressure developed in the supply pump, and thereby normally biased to remain in a position for delivery to the burner from the circulating pump, and return to the latter from the burner, but subject also to pressure developed in the circulating pump and thereby counterbiased to shift from such normal to an emergency position in event of failure of the supply pump, an emergency output conduit connecting the output side of the circulating pump, by way of said circuit control valve when in its emergency position, with the second conduit means between the output side of the supply pump and the throttle means, and arranged for delivery of fuel through the throttle means to the burner from the circulating pump, an emergency input conduit connecting the input side of the circulating pump, by way of said circuit control valve when in its emergency position, with the reservoir, and means operatively associated with the circulating pump, and operatively connectable thereto only through the circuit control valve when the latter is in its emergency position, to vary the delivery of the circulating pump in accordance with pressure in said pump's output as varied by the setting of said throttle means.

2. A fuel supply system as in claim 1, including non-return valves interposed in the first conduit means immediately in advance of and behind the burner and arranged to permit one-way circulation under normal operating conditions, an isolating conduit connected between the second conduit means, at a point intermediate the throttle means and its connection to the first conduit means, and the output side of the first conduit means, at a point between the non-return valve therein and the burner, and an isolating valve in such isolating conduit, normally closed, but arranged to be subject to and opened automatically by the delivery pressure of the circulating pump under emergency conditions, and adapted to connect the latter's output to the burner's input.
3. An emergency fuel supply system as in claim 1, wherein both pumps are of the variable delivery type, means normally operative to retain the circulating pump in a fixed delivery position, an emergency control valve, the emergency output conduit which connects the output side of the circulating pump to the second conduit extending by way of the circuit control valve when the latter is in its emergency position, and thence by way of the emergency control valve to shift the latter, and only thence to the output side of the supply pump in the second conduit means, and means operatively connected to the emergency control valve, operable automatically upon such shifting thereof, to vary the delivery of the circulating pump automatically in accordance with the burner's requirements.
4. A fuel supply system, for the supply of liquid fuel in variable quantities under emergency conditions as well as under normal operating conditions, from a fuel source to a spill type burner, particularly in an aircraft engine, said system comprising in combination, a variable-delivery circulating pump biased to remain fixed in a given delivery position and pressure-sensitive delivery-varying means therefor; a variable-delivery supply pump and pressure-sensitive delivery-varying means therefor; a circuit control valve shiftable between normal and emergency operating positions, respectively; opposed pressure ducts connecting said circuit control valve with the respective pumps, and arranged with relation to the circuit control valve to maintain said valve in normal operating position so long as the supply pump operates, but to shift the circuit control valve automatically to emergency operating position whenever the supply pump fails; a pressure-sensitive isolating valve biased to remain in a normal closed operating position; a pressure-sensitive emergency control valve also biased to remain in a normal operating position; a metering throttle valve; a first, closed circulating conduit means including said circulating pump and said circuit control valve, and adapted to lead fuel thence to the burner, and from the burner back to the circulating pump, by way of said circuit control valve; further, second conduit means including said throttle valve and adapted to lead fuel from the fuel source to the supply pump and thence by way of the throttle valve to a connection with said first, closed, conduit means, to inject fuel into the latter as it is withdrawn therefrom at the burner; a first delivery-controlling duct leading from the pressure side of the supply pump, in advance of the throttle valve, to that pump's delivery-varying means, to regulate automatically 75 the supply pump's delivery in accordance with

variations in the pressure in the second conduit means as determined by the throttle valve's setting; a second delivery-controlling duct leading from the pressure side of the circulating pump, past the circuit control valve, to that pump's delivery-varying means, to regulate automatically the circulating pump's delivery, but the circuit control valve being arranged to close said second delivery-controlling duct so long as said circuit control valve remains in its normal operating position, and to open said second delivery-controlling duct upon shifting to its emergency operating position; a branch duct from said second delivery-controlling duct to said emergency control valve, to apply the pressure of the circulating pump to the emergency control valve to open the latter upon shifting of the circuit control valve to its emergency operating position; an interconnecting duct extending between the emergency control valve and the first delivery-controlling duct, the emergency control valve being arranged to close said interconnecting duct so long as the emergency control valve remains in its biased, normal operating position, but adapted to connect the pressure side of the circulating pump with the second conduit means in advance of the throttle valve by way of the first delivery-controlling duct upon shifting of the emergency control valve from its biased normal operating position; and a third, by-pass conduit means connecting the second conduit means, beyond the throttle valve from the supply pump, with the first conduit means in advance of its connection to the burner, the normally closed isolating valve being interposed in said third conduit means and arranged to be opened by fuel under pressure as supplied by way of said third conduit means.

5. A fuel supply system as in claim 4, including a non-return valve in said first conduit means, at the opposite side of the connection to the latter of the third conduit means from the burner, arranged to permit circulation in the first conduit means during normal operation but to prevent reverse flow in the first conduit means 45 during emergency operation.

6. A fuel supply system as in claim 4, including a non-return valve in said first conduit means, intermediate the burner and the intake side of the circulating pump, arranged to permit return flow from the burner during normal operation but to block reverse flow, the second conduit means being connected to the first conduit means at a point intermediate said non-return valve and the intake of the circulating pump.

10 7. A fuel supply system as in claim 6, and a second non-return valve in said first conduit means, intermediate the delivery side of the circulating pump and the point of connection to said first conduit means of the third conduit means, said non-return valves being arranged to permit one-way circulation in the first conduit means during normal operation but to block reverse flow during emergency operation.

15 8. A fuel supply system as in claim 4, wherein each of the circulating and supply pumps is of the variable displacement type, and its delivery-varying means includes a stroke-controlling element, and wherein the first and second delivery-controlling ducts are connected to the respective 20 stroke-controlling elements to shift the latter under appropriate operating conditions, as defined in claim 4, for variation of the delivery of the corresponding pump.

25 9. A fuel system as in claim 4, wherein each of the pumps is of the fixed displacement type, and wherein the delivery-varying means is constituted by a by-pass and valve normally operatively associated with the supply pump, and connected in the second conduit means, the interconnecting duct constituting part of the third conduit means and being arranged to connect said by-pass and valve to the first conduit means.

FREDERICK HENRY CAREY.
